UNITED STATES PATENT OFFICE.

INGOLF O. SIVERTSEN, OF PROVIDENCE, RHODE ISLAND.

SAVINGS BANK.

Application filed June 16, 1925. Serial No. 37,430.

My invention relates to banks of the box type and has for its essential objects the exposure at all times of a coin receiving slide; security against escape of the contents of the bank; means for automatically discharging the contents of the bank when it is filled; and to attain these ends in a simple, inexpensive, and easily operated structure.

My invention consists in such parts and combinations of parts as fall within the scope of the appended claims.

In the accompanying drawings which form a part of this specification—

Figures 1 and 2 are a top plan view and 15 a front elevation respectively of a bank embodying my invention,

Figures 3 and 4 are sections on line 3—3 of Figure 2 showing the carriers in normal position and in an intermediate position respectively,

Figures 5 and 6, sections on lines 5—5 and 6—6 respectively of Figure 2,

Figures 7 and 8, sections on lines 7—7 and 8—8 respectively of Figure 2,

Figure 9, a front elevation of the latch 25 showing adjacent parts in section, and

Figures 10 and 11, perspective views of a carrier block and its shell respectively.

Like reference characters indicate like 30 parts throughout the views.

The bank comprises a casing 15 which includes a base 17, a front 18, a back 19, sides 20, a top 22, and a horizontal partition 23 near the top. There are openings 25 in the 35 upper portion of the front adjacent the sides to accommodate carriers 26 slidable transversely of the casing on the partition and guided by strips 27 upon the latter. In the rear of the partition in the paths of the carriers are coin ejection holes 28. Each carrier 26, as shown in Figure 11, comprises a shell 31 having an oblong base 32, a closed front 33, sides 34, and a top 35. The top and one side extend only a portion of the 40 length of the base. The top and extending or rear portion of the base have respectively a coin receiving and coin delivery opening 36 and 37. Integral with the top 35 is a lateral lug 39 provided with a pivot pin 40.

One base 32 has a rear corner diagonally 45 cut away to form a cam edge or face 41 for a purpose to be hereinafter stated.

Slidably mounted in each shell is a block 42, shown in detail in Figure 10 provided 50 with a central coin orifice 43. The rear end of the block is provided with a transversely

disposed slot 44 opening into a similarly disposed groove 45 of greater width forming retaining flanges 46.

Upon the partition 23 is fixed a block 49 60 upon which is mounted a double lever, indicated generally by 50. The lever in this instance comprises a body portion 51, lateral arms 52 upon the body portion provided with longitudinal slots 53 in their ends, and 65 a pair of lateral curved arms 55. The lever is pivoted to the block 49 by a pin 57 passing through a hole 58 in an intermediate portion of the lever member 50. The pins 40 are slidable in the slots 53, and pins 60 on 70 the ends of arms 55 are slidable in the grooves 45. The arms 52 of the lever member are operated by the shells 31, and the arms 55 operate the blocks 42, by a pivotal sliding movement. Each coin carrier 26 is 75 thus simultaneously reciprocated in an opposite direction. In its extreme advanced position a carrier projects beyond the front of the casing sufficiently to expose the coin receiving opening 36 and the orifice 43 of 80 the block 42, which is in normal position. The other coin carrier 36 is simultaneously housed. The lugs 39 form stops to excessive forward travel of the carriers, while the back of the casing constitutes a stop in the 85 opposite direction. In Figure 1 the left hand carrier is shown in receiving position, and its block 42 is housed in its shell 31. Assuming a coin to be dropped into the opening 36, and the carrier to be manually pushed 90 rearwardly, the block 42 will advance with the coin, but at a greater rate of speed, so that it contacts with the casing back simultaneously with the shell base 32, at which instant the opening 37 and hole 38 register with each other, and the coin is in position to drop by gravity through the hole 28. The left hand carrier is now housed and the right hand carrier is exposed.

In order to prevent any accidental return 100 of the coins from below the partition, a strip 62 of resilient material is fixed by screws 63, in an intermediate portion, to the lower face of the partition 23, as shown in Figure 5. Screws 65 in the free ends of the strip engage closure disks 66 which are loosely supported in the holes 28. The weight of a coin sufficiently depresses a disk to permit passage into the lower compartment of the casing, but the disks resist excessive pressure or weight in an opposite direction.

The front wall of the casing includes a

swinging door 69 closing a rectangular aperture 70 extending to the base 17. The door is pivoted at its top, in this instance by lateral pins 71 extending into cavities 72 in the casing. Upon the rear face of the door, near its bottom is a catch 73 consisting of a block 74 provided with a vertical groove 75. Adjacent the catch the floor 17, as shown in Figure 9, has an oblong cavity 76 across which extends a pivot pin 77 upon which is pivotally mounted a vertical latch 78 comprising a body 79 provided in its rear face with a vertical transversely T shaped groove 80 in which is slidably seated a vertical rod 83 or plate 83 having upon its lower end a horizontal rearwardly directed arm portion 85 provided with an oblong slot 87. A vertical lateral rib 88 upon the body 79 is adapted to enter and leave the catch slot 75 as the latch body is vibrated upon its pivot 77. The rod 83 is maintained in normal or depressed position by a helical spring 89 attached at one end to a pin 90 on the top of the body 79 and at its other end to a pin 91 in the rod 83 above the body.

The latch is moved through a vibratory lever 92 pivoted intermediate its length upon a pin 93 to the lower face of the partition 23, as shown in Figure 5. A pin 94 in the upper face of the lever, near one end, projects through an arcuate slot 95 in the partition. One end of this slot, as shown in Figure 4, is in the path of the cam edge 41 of the carrier base 32. The pin 94 is held in constant contact with this carrier by a helical spring 95* attached at one end to a pin 96 on the end of the lever and a pin 97 in the partition. Hence at each reciprocation of the carrier the lever 92 is vibrated. When the rod 83 is in elevated position its upper extremity is in the path of the lateral edge of the lever 92 which moves the rod and body 79 laterally, as shown in broken lines in Figure 9, thus withdrawing the rib 88 from the latch groove 75 and freeing the door 69.

The elevation of the rod 83 is effected as follows. A plate or floor 98, normally inclined upwardly and rearwardly covers the base 17, and has a rear longitudinal portion or strip 99 engaging the back 19, and flexibly connected with the main portion of the plate by resilient plates 100 fixed by pins 101 or otherwise to said portions. The lower forward portion of the floor is flexibly connected with the base by similar flexible plates 102 fixed by pins 103 thereto. In this instance the floor 98 is covered with a fabric 104 and is overlapped by a longitudinal stop 105 fast to the back 19. A plate 106 is attached to the rear upper face of the floor and has ears 107 carrying a pivot pin 108 in the rear end of a link lever 109 comprising a link portion 110 and an intermediate lever arm 111 depending from the

link, and passing through an oblong slot 112 in the floor, with its rounded end resting on the base 17. Upon the forward end of the link portion of the lever is a pin 113 movable in the slot 87. In this instance a helical spring 114 has its ends attached to the link 109 and floor 98, but this spring may be omitted.

As the coins entering the lower compartment of the casing increase in number their cumulative weight gradually depresses the member 98 upon which they rest, until the compartment is full and said member reaches a horizontal or nearly horizontal position. During this descent the fulcruming lever 80 arm 111 sliding along the base 17 shifts its direction, as shown in broken lines in Figure 7. The described descent of the member 98 elevates the rod 83, through the member 109, into the path of the lever 92, and the door 69 is thereupon unlatched, permitting the weight of the accumulated coins to swing the door outwardly, to some such position as shown in broken lines in Figure 7, and escape. The floor 98 relieved of the weight of the coins is returned to original elevated position by the spring 89 and, when present, the spring 114.

I claim:

1. In a savings bank, a casing provided with coin holes, reciprocable coin carriers slidably mounted in the casing and provided with coin orifices adapted to alternately register with the holes, means for reciprocating the carriers and coin-releasing means actuated by the weight of the coins for delivering the coins.

2. In a savings bank, a casing provided with holes, reciprocable coin carriers slidably mounted in the casing and provided with coin orifices adapted to alternately register with the holes, a lever member supported by said casing and connecting the carriers and coin-releasing means actuated by the weight of the coins for delivering the coins.

3. In a savings bank, a casing provided with openings in its front portion and a partition with coin holes, reciprocable coin carriers slidably mounted in the casing and alternately movable exterior of the casing, said carriers being provided with orifices adapted to alternately register with the holes, a lever member pivotally supported in the casing and attached at its ends to the carriers and coin-releasing means actuated by the weight of the coins for delivering the coins.

4. In a savings bank, a casing provided with holes, reciprocable coin carriers slidably mounted in the casing and being provided with coin orifices adapted to alternately register with the holes, closure disks yieldingly supported by the casing in the holes, a lever member connecting the carriers and pivotal-

ly mounted in the casing between the carriers and coin-releasing means actuated by the weight of the coins for delivering the coins.

5. In a savings bank, a casing provided with coin ejection holes, reciprocable coin carriers comprising shells slidably mounted in the casing and provided with coin receiving openings near their forward ends, and with coin delivery openings near their rear ends adapted to register with the ejection holes, and reciprocable blocks slidably mounted in the shells and provided with coin orifices adapted to register with the coin receiving openings and with the coin delivery openings of the shell, a lever member pivotally supported by the casing between the carriers comprising arms engaging the shells, and arms engaging the blocks.
6. In a savings bank, a casing comprising a base, a top, and side walls, one of the walls being provided with carrier openings, and with a coin discharge opening below the carrier openings, a swinging door pivotally supported in said wall in the discharge opening, and a horizontal partition fixed to the walls below the carrier openings and provided with coin ejection holes, reciprocable coin carriers slidably mounted upon the partition in the carrier holes said carriers being provided with coin orifices adapted to alternately register with the ejection holes, a lever member connecting the carriers and pivotally mounted on the partition between the carriers, a vibratory lever pivotally supported upon the partition and actuated by one of the carriers, a catch upon the door, a vibratory latch pivotally supported by the base, and normally engaging the catch, a vertically reciprocable rod slidably mounted in the latch vertically movable into the path of the vibratory lever, a spring connecting the latch and rod, a rearwardly and upwardly inclined depressible floor yieldingly attached to the base adjacent the door, a plate upon the elevated portion of the floor, a link pivotally attached to the plate and connected with the rod, and a fulcruming arm upon the link adapted to cooperate with the base.

movable into the path of the vibratory lever, 40 and yielding means actuated by the weight of coins admitted through the ejection holes for actuating the rod to release the latch from the catch.

7. In a savings bank, a casing comprising 45 a base, a top, and side walls, one of the walls being provided with carrier openings, and with a coin discharge opening below the carrier openings, a swinging door pivotally supported in said wall in the discharge opening, 50 and a horizontal partition fixed to the walls below the carrier openings and provided with coin ejection holes, reciprocable coin carriers slidably mounted upon the partition in the carrier holes said carriers being provided with coin orifices adapted to alternately 55 register with the ejection holes, a lever member connecting the carriers and pivotally mounted on the partition between the carriers, a vibratory lever pivotally supported upon the partition and actuated by one of the carriers, a catch upon the door, a vibratory latch pivotally supported by the base, and normally engaging the catch, a vertically reciprocable rod slidably mounted 60 in the latch vertically movable into the path of the vibratory lever, a spring connecting the latch and rod, a rearwardly and upwardly inclined depressible floor yieldingly attached to the base adjacent the door, a plate 65 upon the elevated portion of the floor, a link pivotally attached to the plate and connected with the rod, and a fulcruming arm upon the link adapted to cooperate with the base.

In testimony whereof I have affixed my 75 signature.

INGOLF O. SIVERTSEN.
